ATTORNEY

UNITED STATES PATENT OFFICE.

JAMES M. LAWLER, OF TOPEKA, KANSAS.

SCREW-DRIVER ATTACHMENT.

Application filed April 24, 1922. Serial No. 556,170.

To all whom it may concern:

Be it known that I, JAMES M. LAWLER, a citizen of the United States, residing at Topeka, in the county of Shawnee and State of Kansas, have invented certain new and useful Improvements in Screw-Driver Attachments; and I do declare the following to be a full, clear, and exact description of the invention, such as will enable others skilled in the art to which it appertains to make and use the same, reference being had to the accompanying drawings, and to the figures of reference marked thereon, which form a part of this specification.

15. This invention relates to a screw holding attachment for screw drivers and the object is to provide a novel form of attachment which may be readily applied to existing types of screw drivers in such a manner that 20 the screw can be held in position to cause the blade of the screw driver to engage the groove in the head of the screw.

The attachment can be instantly applied and detached from the screw driver shank.

25. In the drawings,

Fig. 1 is a perspective view of a screw driver with the attachment applied.

Fig. 2 is an elevational view of the attachment applied.

30. Fig. 3 is an end view of the attachment applied.

Fig. 4 is an enlarged sectional view through the attachment, showing the screw held in place and engaged by the end of the 35 screw driver shank.

Fig. 5 is a detail perspective view of the detached expansion spring.

Fig. 6 is a sectional view on the line 6—6 of Fig. 4, and

40. Fig. 7 is an elevational view of one of the attachment members with the spring in place.

The attachment consists of duplicate, complementary members 1 and 2, concavo-convex longitudinally. The two members are provided at their lower ends with tubular portions 3 and 4, having in-turned lips 5 and 6 to engage the under side of the head 7 of a screw 8 in such a position that the shank 9 of the screw driver 10 may engage the groove 11.

The two members are each provided with ears 12 and 13 at one edge and prongs 14 and 15 at their opposite edges, the prong of one member extending through an opening in the ear of the other member so that a

hinge joint is made to provide a fulcrum for pivoting the two members together.

Each member is a duplicate of the other, there being no rights and lefts. Therefore, 60 the parts need not be matched because the prong of one will enter the opening in the ear of the other member, as will be clearly apparent by reference to Fig. 6.

The upper ends 16 and 17 of the members are flattened and somewhat enlarged. The member 1 has notches 18 and 19 opposite notches 20 and 21 on the member 2. These notches receive the expansion spring 22. The expansion spring consists of a curved 70 bar 23 having parallel arms 24 and 25 with outbent portions 26 and 27, curved down in substantially parallel members 28 and 29 and then bent upwardly at 30 and 31, terminating in the ends 32 and 33. The portions 75 26 and 27 are adapted to lie in one set of notches, 18 and 19, for example, and the ends 32 and 33 are adapted to lie in the opposite notches, so the spring is held between the ends 16 and 17, tending to cause the turned-over portions or lips 5 and 6 to engage under the screw head 7.

The spring constitutes an expansion spring for normally forcing the upper ends apart, as will be clearly apparent by reference to Figs. 1, 2, 3 and 4. The ears 12 and 13 and the prongs 14 and 15 are bent toward the walls of their respective complementary members so that liability of the two members becoming detached will be 80 eliminated and since the spring normally forces the upper ends of the two members apart, it will be apparent that the lower ends may engage the screw. The curved portion will bear against the shank 9 of the screw driver as it is forced between the two members, as shown in Figs. 1, 2, 3 and 4, the portion 23 constituting a friction member for engaging the shank of the screw driver so that it will be held from slipping. 90

When the attachment is applied to the shank, the two members can pivot one upon the other so that the lips or jaw members 5 and 6 will open to receive the head of the screw and to permit the shank 9 to engage the groove thereof, then the screw can be introduced into the wood and screwed home in a convenient manner, as will be apparent by reference to the drawings.

The device is capable of other uses than that of a screw driver attachment, as it may be used as a clip for holding papers and the

like and in that case, the attachment may be provided with openings 34 in the upper ends of the members 1 and 2 so that it can be hung from a nail or support. The device is primarily intended, however, as a screw driver attachment for holding screws and it will be apparent from the foregoing that it may be readily attached to an existing type of screw driver of appropriate size.

10 The attachment can be made in any size to fit the particular kind of a screw driver employed.

What I claim and desire to secure by Letters-Patent is:

15 1. A screw driver attachment for screws comprising two complementary members pivoted together and having screw-engaging jaws, in combination with an expansion spring consisting of a bar having parallel, 20 outstanding arms at the ends of which are outstanding portions, substantially parallel arm members carried by the outstanding portions, the members being bent upward, the spring being positioned between the two

complementary members beyond the point 25 at which they are pivoted so that the other ends of the members will be forced one toward the other, the spring forming a loop through which the screw driver may be inserted so that the screw driver can pass between the two complementary members.

2. A screw driver attachment for holding screws comprising two complementary members pivoted together and having screw-engaging jaws, in combination with a spring 35 for forcing complementary ends of the members apart and other complementary ends of the members together, the spring comprising a curved bar having upstanding arms, downwardly projecting arms carried by the upper ends of the upstanding arms, and upwardly curved ends on the last-named arms, the bar of the spring lying to one side of the longitudinal center of the attachment when the spring is in place.

45 In testimony whereof I affix my signature.

JAMES M. LAWLOR.
